METHOD OF TAKING UP THE PLAY OF SPIKES

Albert Paul Streit, Cachan, France

Original application November 30, 1937, Serial No. 177,364. Divided and this application June 3, 1940, Serial No. 338,605

3 Claims. (Cl. 238—373)

The present application is a division of my co-pending application Ser. No. 177,364, filed Nov. 30, 1937, and issued as Patent No. 2,222,546, Nov. 19, 1940.

This application relates to the fixation of non-circular spikes in holes of corresponding shape provided in wooden railway sleepers.

The chief object of the present invention is to provide a method of treating railway sleepers so as to permit of replacing a prismatic, and in particular square-shaped, spike having a worn out hole by another spike of corresponding shape.

Other objects of the present invention will result from the following detailed description of some specific embodiments thereof.

A preferred embodiment of the present invention will be hereinafter described, with reference to the accompanying drawing, given merely by way of example, and in which:

Fig. 1 is a vertical section of a railway track showing the wooden sleeper, the rail, and the spike, in position;

Fig. 2 is a horizontal sectional view on the line II—II of Fig. 1;

Fig. 3 is a perspective view of the spike shown by Figs. 1 and 2;

Fig. 4 is a perspective view of a mandrel provided with a lining, for use according to the invention;

Fig. 5 is a view on an enlarged scale showing the section of the lining;

Fig. 6 is a cross section of the hole formed in the sleeper, after the lining has been placed therein;

Fig. 7 is a similar cross section showing the deforming of the hole;

Fig. 8 is a similar cross section illustrating the driving of the spike into the hole after the lining thereof has been deformed;

Fig. 9 is a vertical sectional view showing the spike in position;

Fig. 10 is a partial view on an enlarged scale corresponding to Fig. 9;

Fig. 11 is a sectional view on the line XI—XI of Fig. 10;

Fig. 12 is a sectional view, analogous to Fig. 8, corresponding to the case of a spike having a square-shaped end instead of a bevelled end.

As shown by Fig. 1, in a railway track, each rail 1 is kept in position on a sleeper 2 by means of spikes such as 3. Each of said spikes, of square section for instance, is driven into a hole 4 of circular section, made in advance in sleeper 2, so that the nose 5 of the spike is applied against the flange 6 of rail 1.

When the spike has worked loose in its hole, it becomes necessary to replace it.

For this purpose, according to the invention, I make use of a lining 7, helically wound in the hole and of V-shaped section, with the apex of the V on the outside so as to cut into the wall of the hole, said lining being made of a malleable metal or alloy, rust-proof and having a high coefficient of elongation, for instance of annealed brass.

As shown by Fig. 5, the thickness of the branches of the V decreases from the apex toward the edges 7b.

In order to place the lining in position inside the hole, said lining is helically wound around a threaded mandrel 9 of circular section, the diameter and size of the threads of said mandrel being such that when the lining is coiled thereon, as shown by Fig. 4, the outer diameter of the coil is larger than the length of the side of the square hole but smaller than the diagonal thereof.

As shown by Fig. 4, the driving end of the mandrel is provided with an eye in which the end of the coil can be engaged so as to fix it to the mandrel during the screwing thereof.

When the lining has thus been fitted on mandrel 9 as shown by Fig. 4, the whole is screwed into the hole existing in the sleeper.

The mandrel is then removed by unscrewing, which immediately breaks the end of the lining engaged in the hole of the mandrel. Therefore, during this unscrewing operation, lining 7 remains in the hole, into the walls of which it has cut during the screwing operation, owing to its V shape.

After removal of the mandrel, lining 7 remains in position in hole 4, as shown by Fig. 6.

The new spike 3 is then hammered into the hole thus lined, so as to obtain a final fixation as shown by Fig. 9, Fig. 10 and Fig. 11.

This driving of the square-shaped spike into the lined hole produces a further penetration of the lining into the wood of the sleeper. Furthermore, the coiled band which constitutes the lining is wedged between the wall of the sleeper and the walls of the spike, and especially the edges thereof, thus tightly holding said spike in position in said hole.

Advantageously, according to the invention, in order to prevent the threads of the lining coil from being battered down by the opposed edges 3b (Fig. 3) of the spike when the latter is being driven into the sleeper hole, said hole, after it has been fitted with its coiled lining, is given an

oval section by previously driving therein a tool of suitable section, diagrammatically illustrated at 10 (Fig. 7). As a consequence of the driving of said tool 10, the ridges 7a of the lining coil penetrate more deeply into the wood of sleeper 2, while edges 7b are slightly moved away from said wood wall.

After removal of tool 10, the spike can be driven into the sleeper hole. Fig. 8 shows that the bevelled end 3a of the spike can freely engage into the sleeper hole, owing to the oval shape given thereto, without touching the first threads of coiled lining 7.

Instead of having a bevelled end as shown by Fig. 3, the spike may have a pointed end, that is to say have its four faces inclined. In this case, it is advantageous to deform the sleeper hole in two directions at right angles to each other, as shown at F₁ and F₂ in Fig. 12. This deformation is obtained by means of a tool of tapered shape having four ridges at 90° to one another.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A method of securing a spike of square section into a wooden railway sleeper having a spike hole of corresponding section formed therein, by means of a rod of malleable metal and of V-shaped channel cross section and a screw-threaded mandrel, which comprises winding said rod onto said mandrel into a coil with the groove of the V engaging the thread of the mandrel, the outer diameter of the coil being smaller than the diagonal of the sleeper hole square section but larger than the side of said square section, securing the driving end of the coil to the end of the mandrel, screwing the coil on the mandrel into a portion of the walls of said hole, unscrewing the mandrel from the coil thereby detaching

the mandrel therefrom, enlarging the hole thus lined along at least one diameter thereof, and driving into the hole thus treated a spike of square section and straight edges having its end flattened in the direction of said diameter.

2. A method of securing a spike of square section into a wooden railway sleeper having a spike hole of square section formed therein, by means of a rod of malleable metal and of V-shaped channel cross-section and of a screw-threaded mandrel, which comprises winding said rod on said mandrel into a coil with the groove of the V engaging the thread of the mandrel, the outer diameter of the coil being smaller than the diagonal of the sleeper hole square section, securing the driving end of the coil to the end of the mandrel, screwing the coil on the mandrel into a portion of the walls of said hole, unscrewing the mandrel from the coil thereby detaching the mandrel therefrom, enlarging the hole thus lined along one diameter thereof, and forcing a square spike having a flat tapered end into the sleeper hole lined with said coil, with the flat end of said spike in the plane of said diameter of the hole.

3. A method of securing a spike of square section in a wooden railway sleeper having a spike hole of corresponding section formed therein, by means of a rod of malleable metal and of V-shaped channel cross section and of a screw-threaded mandrel, which comprises winding said rod on said mandrel into a coil, with the groove of the V engaging the thread of the mandrel, the outer diameter of the coil being smaller than the diagonal of the sleeper hole square section, securing the driving end of the coil to the end of the mandrel, screwing the coil on the mandrel into a portion of the walls of said hole, unscrewing the mandrel from the coil thereby detaching the mandrel therefrom, enlarging the hole thus lined along two perpendicular diameters thereof, and forcing a square spike having a square tapered end into the sleeper hole lined with said coil, with the diagonal planes of the spike in said diametral planes of said hole.

ALBERT PAUL STREIT.
